METHOD OF MAKING EVAPORATORS

Bernard C. Johnson, Libertyville, Ill., assignor to
Houdaille-Hershey Corporation, Detroit, Mich.,
a corporation of Michigan

Application December 12, 1940, Serial No. 369,722

1 Claim. (Cl. 29—157.3)

This invention relates to methods for forming rounded edges on metal articles to eliminate sharp angles in order that coating material will uniformly cover the articles.

Specifically this invention relates to the pressing of the edges and aperture mouths of sheet metal evaporator units to eliminate all sharp corners therefrom in order that the evaporator unit can be uniformly coated with protective films such as zinc.

While the invention will be hereinafter specifically described in connection with sheet metal evaporator units, it should be understood that the principles of the invention are applicable to metal articles in general.

Metal articles having sharp edges cannot be uniformly coated since the coating film will be quite thin at these edges and, in numerous instances, the sharp edges will project through the film. In the manufacture of sheet metal evaporator units from inexpensive metals such as mild steel, it is necessary to thoroughly protect all exterior surfaces of the unit with a protecting film. Such sheet metal evaporator units are usually galvanized or tinned, and it is very difficult to cover the sharp edges of the unit with such a protective metal film inasmuch as the film will draw thin or break entirely at the edges of the articles.

The present invention now overcomes the heretofore encountered difficulty by dressing all sharp edges and corners of a sheet metal evaporator unit to provide rounded contours thereon which are readily covered with protective film. The dressing operations can be performed by working or pressing the peripheral edges and annular aperture mouths of the sheet metal unit. For example, the sheet metal can be passed between grooved rollers which will round off the peripheral edges of the unit. Any apertures in the unit can be die-pressed to round off the sharp aperture mouths. These dressing operations are preferably effected prior to the bending of the unit into its final shape and while the same is still in a flat condition.

It is, then, an object of this invention to prepare the edges of metal articles for coating by dressing these edges to form a round contour thereon.

Another object of the invention is to work the metal edges of sheet metal articles into rounded shape for eliminating sharp angles.

A specific object of the invention is to press the linear peripheral edges and annular aper-

ture mouths of a sheet metal evaporator unit for forming rounded contours thereon.

Other and further objects of the invention will be apparent to those skilled in the art from the following detailed description of the annexed sheets of drawings which, by way of example, illustrate a preferred embodiment of the invention.

On the drawings:

Figure 1 is a front end elevational view of a U-shaped sheet metal evaporator unit with rounded edges and aperture mouths formed according to this invention and illustrating in dotted lines the manner in which the unit is bent from flat sheet form.

Figure 2 is a side elevational view of the evaporator unit shown in Figure 1.

Figure 3 is an enlarged fragmentary horizontal cross-sectional view taken along the line III—III of Figure 2 and illustrating a uniform coating around an edge of the unit.

Figure 4 is a view similar to Figure 3 but illustrating the deficient coating film on an article having a sharp edge.

Figure 5 is a top plan view of a dressing machine for rounding the longitudinal edges of embossed welded-together flat metal sheets forming the body of the evaporator unit and illustrating the passage of the unit through the machine.

Figure 6 is an end elevational view of the machine and embossed welded-together metal sheets passing through the machine as shown in Figure 5.

Figure 7 is an enlarged vertical cross-sectional view taken through one form of die for rounding the mouths of an aperture in the metal sheet shown in Figure 5.

Figure 8 is a view similar to Figure 7 but illustrating the die in fully closed position and showing the manner in which the sheet metal is pressed to provide a rounded contour for the aperture.

Figure 9 is a view similar to Figure 7 but illustrating a modified form of die for rounding the aperture mouths.

Figure 10 is a plan view of an apertured metal sheet illustrating a rounded aperture mouth formed in accordance with this invention.

Figure 11 is a view taken along the line XI—XI of Figure 10 and illustrating the uniform protecting film covering the sheet metal.

Figure 12 is a view similar to Figure 11 but illustrating the defective protecting film formed when the aperture mouths are sharp.

As shown on the drawings:

In Figures 1 and 2, the reference numeral 10 designates generally a U-shaped sheet metal evaporator unit defining the side walls and bottom of a sharp freezing chamber 11. The unit is composed of an outer sheet 12 welded, brazed, or otherwise secured to an inner sheet 13.

Prior to securing the sheets 12 and 13 together, the sheet 12 is embossed to provide flutes 14 defining refrigerant circulating ducts along the side walls and bottom of the unit and semi-cylindrical header depressions 15 and 16 normal to the flutes 14 at the ends of the sheets. The sheet 12 is also embossed to provide a flute 17 in intersecting relation with the flutes 14 to serve as an inlet manifold for supplying refrigerant to the circulating ducts. The inner sheet 13 is embossed with semi-cylindrical depressions 18 and 19 complementary with the depressions 15 and 16 to cooperate therewith for forming header chambers in the side walls of the unit. The inner sheet is also embossed as at 20 to provide ducts joining the header chambers. The outer sheet can be further embossed to provide a flute 21 around the side walls and bottom thereof connecting the tops of the top header chambers in the side walls. This flute 21 defines an outlet passageway for spent refrigerant to be removed therethrough from the unit.

As shown in Figure 1, in dotted lines, the unit 10 is formed by bending, into U-shape, the flat embossed welded-together sheets 12 and 13 which provide a blank designated generally by the reference numeral 25. The blank 25 can be readily formed around a shaping die into the desired evaporator unit shape for providing the side walls and bottom of a sharp freezing chamber. The upper ends of the side walls of the bent unit are preferably turned in to form hanger flanges 26.

As best shown in Figure 5, the flat blank 25 has apertures 27 at the ends thereof which apertures will be through the flanges 26 when the unit is bent into final form to receive hanging bolts. The blank 25 also has additional apertures therethrough such as 28 to provide for the mounting of a shelf in the unit; 29 to provide for the mounting of a thermostat bulb or other temperature-responsive means on the unit; and 30 to provide for the mounting of a door across the open front face of the unit.

As shown in Figures 5 and 6, the blank 25 has the longitudinal edges 31 thereof acted on by means of a machine 32 composed of a block 33 carrying spaced pairs of grooved rollers 34, 35 and 36 rotatably mounted on vertical axles 37 carried by the block. The rollers each have peripheral rounded grooves 38 therearound. The first pair of rollers 34 is spaced apart for a distance greater than the distance between the second pair of rollers 35 and this second pair of rollers 35 is, in turn, spaced apart for a distance greater than the third pair of rollers 36.

The blank 25 is passed through the machine 32 in the direction indicated by the arrow in Figure 5 so that the first pair of rollers 34 will initially act on the sharp longitudinal edges of the blank and will start to dress the edges. Then, as the blank is pushed through the machine and between the succeeding pairs of rollers the rounded grooves 38 of the rollers will press the edges 31 to conform with the rounded shape of the grooves and thereby eliminate the sharp edges. As shown in Figure 3, the edges of the welded-together sheets 12 and 13 will thus have a semi-cylindrical contour 39. After passage through

the machine 32 the blank 25 is then passed through another machine similar to the machine 32 but having pairs of rollers spaced to act on the edges 40 of the blank. The resulting blank 5 will therefore have all peripheral edges free from sharp corners and, as shown in Figure 3, a galvanized coating 41 on the finished unit will provide a film which flows evenly all around the edges as at 42.

10 If, on the other hand, as shown in Figure 4 the sheets 12 and 13 had sharp edges 43 at right angles to the faces of the sheet, a galvanizing film 41 would be quite thin at the sharp corners 44 and might even break to expose these corners.

15 From the above descriptions it will thus be understood that all linear peripheral edges of the blank 25 are dressed to eliminate sharp edges and to provide rounded contours to the edges which 20 will be uniformly covered with a protecting film upon dipping the metal article in the coating material.

It has heretofore been considered necessary to 25 line all apertures through sheet metal evaporator units with copper ferrules for protecting the sheet metal against corrosion. These ferrules were required even though the units were galvanized inasmuch as the sharp mouths of the apertures would not be uniformly covered with the zinc film. The present invention now eliminates the necessity for copper ferrule liners and at the same time insures the formation of uniformly thick films over the aperture walls.

Thus, as shown in Figures 7 and 8, an aperture 35 of the blank 25 such as a hole 27 through the sheets 12 and 13 is dressed in a die for removing the sharp aperture mouths 45. The blank 25 is mounted on a die 46 with the aperture 27 receiving the leading end of the die. This 40 leading end of the die has a quarter-round bevel or groove 47. A top die 48 having a similar leading end with a rounded groove 49 cooperates with the die 46. The dies 46 and 48 are telescoped by sleeves 50 and 50a respectively 45 which have rounded leading ends 51.

The leading ends 51 of the sleeves press into the faces of the sheets 12 and 13 to flow a metal into the aperture 27. As the dies close, the grooves 47 and 49 form a semi-cylindrical pocket 50 which receives metal pressed from the faces of the sheet by the sleeves 50 and 50a to form a rounded periphery 52 for the aperture 27. The metal pressed by the leading ends 51 of the sleeves, together with the metal pressed from the sharp corners 45 will completely fill the die cavities as shown in Figure 8.

All of the apertures 27 to 30 of the blank 25 may be treated in a similar manner to dress the aperture mouths for eliminating all sharp corners.

60 Alternatively, as shown in Figure 9, the sleeves 50 and 50a may be omitted from the dies 46 and 48. The quarter-round grooves 47 and 49 of the dies will dress the sharp corners 45 of the aperture 27 sufficiently to form a rounded contour, although this rounded contour may not be as smooth as that obtained with the use of the sleeves. It is, nevertheless, sufficient for insuring uniform covering with a protective film.

As shown in Figures 10 and 11, the finished unit 10, with the rounded holes 27 can then be galvanized to form the protective film 41 described above. This protective film 41 will flow through the apertures 27 and be uniformly deposited thereon as at 53. If, on the other hand,

as shown in Figure 12, the corners 45 are allowed to remain around the aperture mouths, the film 41 will not uniformly flow through the aperture and will draw thin or rupture as at 54.

It will thus be understood that the invention also includes the elimination of sharp corners from apertures through sheet metal articles in order that coating material will uniformly flow through the apertures to provide a protecting film for the metal covering all exposed surfaces of the metal.

It will, of course, be understood that various details of the invention may be varied through a wide range without departing from the principles of this invention and it is, therefore, not the purpose to limit the patent granted hereon otherwise than necessitated by the scope of the appended claim.

I claim as my invention:

In the method of manufacturing an evaporator unit including the steps of embossing a pair of flat, thin metallic plates to provide refrigerant ducts and headers therefor when said plates are united, providing mating apertures in said plates

for mounting purposes, uniting said plates in mated relationship, bending said united plates to form an evaporator unit including the side and bottom walls of a quick-freeze chamber and providing a protective coating over the surface of said unit, the step of preparing said unit for the application of said protective coating to insure a uniform coverage thereover and particularly over the edges of the mating apertures and over the mating peripheral edges of said unit, which edges are initially sharp and therefore difficult to cover completely and uniformly by said protective coating, which step comprises rounding the corners at all peripheral edges and aperture edges while the united plates are in a flat state by forcing metal simultaneously from opposite sides of the evaporator unit at each edge toward the junction between said plates at said each edge so as to round the corners at both sides of the peripheral edges and aperture edges and thereby minimize the possibility of any sharp corners projecting through said protective coating.

BERNARD C. JOHNSON.
